Attorney

UNITED STATES PATENT OFFICE.

JOSHUA WEINGARTEN, OF PHILADELPHIA, PENNSYLVANIA.

SHOE FASTENING.

Application filed October 24, 1927. Serial No. 228,307.

This invention relates to shoe fastenings and has for its object the provision of a shoe lace which will effectually hold a shoe closed closely, neatly and comfortably upon the 5 foot of the wearer and which will need no readjustment after the shoe has once been closed, but will permit the shoe to be readily removed when desired.

The invention is illustrated in the accompanying drawing and will be hereinafter fully described, the novel features being particularly pointed out in the appended claim.

In the drawing:—

15 Fig. 1 is a perspective view of a shoe having my improved lace applied thereto;

Fig. 2 is a perspective view of the lace on a larger scale;

20 Fig. 3 is a plan view of the tip end of the lace and the holder applied thereto; and

Fig. 4 is a detail showing the lace in elevation and the holder in section.

The shoe 1 may be a low shoe, as shown or a high shoe, and is provided with the usual lacing eyelets 2. The shoe may be of leather, canvas, or other suitable material, and it is to be understood that while the invention is intended more particularly for closing shoes, it may be employed wherever 25 two edges provided with rows of openings are to be brought into closed relation. The lace 3 is a strand of elastic material preferably circular in cross section and of proper diameter to pass easily through the eyelets 30 2 when being applied. To one end of the lace is attached a stop or anchor consisting of a thin flat disk 4 having a central opening through which the strand is inserted, the extremity of the strand being clamped or fas- 35 tened to the disk 4, or otherwise secured against withdrawal. The opposite end of the strand is provided with the usual tip 6 whereby it may be inserted in and draw the 40 eyelets successively to be laced back and forth, as shown in Fig. 1. When the lace has been properly threaded through a bottom eyelet, the anchoring disk 4 will lie be- 45 tween the flap and tongue of the shoe so that the end of the disk will be held in the eyelet without causing any discomfort to the wear- 50 er of the shoe. The tip end of the lace will extend beyond the top of the shoe and may drop over the edge of the shoe. To prevent withdrawal of the free end of the lace, I en-

gage a guard or holder 7 therewith close to the shoe, the guard, like the anchoring disk 4, being of such size that it cannot pass through an eyelet. The guard or holder consists of a short length of wire bent into U-form and having the sides of the U 55 crimped, as shown at 8, whereby convolutions are produced defining alternate contracted and expanded portions in the width of the holder. The ends of holder diverge, as shown at 9, and the lace may, therefore, be readily engaged between the sides of the holder. The lace, having been engaged between the sides of the holder, is moved into the bight thereof as shown in full lines in Fig. 2, and will then be retained between the closed end of the holder and the intermediate contracted portion thereof, although the holder may be slid along the lace to be adjusted close to the upper edge of the shoe or the top eyelet. When the proper adjustment has 60 been obtained, the free end portion of the lace is bent over the contracted portion 10 of the holder and engaged through the expanded portion between the same and extremities of the sides of the holder, as shown clearly 65 in Figs. 3 and 4. The holder will thereby be so mounted on the lace that it will not move under ordinary strains and, consequently, unlacing of the shoe cannot occur unless the wearer deliberately applies suffi- 70 cient force to release the lace. Inasmuch as the lace is of elastic material, it will yield to permit removal or donning of the shoe and will at once retract to hold the shoe to the 75 foot in a neat fit. After the holder has been 80 once adjusted, the lacing will need no attention unless renewal should be required after 85 long-continued use.

Having thus described my invention, what I claim as new and desire to secure by Letters Patent of the United States, is:—

A fastening device comprising a lacing strand, an anchoring element at one end of the strand, and a guard consisting of a U-shaped member having its width alternately 100 expanded and contracted, the lacing strand passing through an expanded portion of the guard in one direction, over a contracted portion, and through a second expanded portion in the opposite direction.

In testimony whereof I hereunto affix my signature.

JOSHUA WEINGARTEN.
